FLOWER POT

Leon Tisset, 22 Rue de Mercier, Nantua, France

Filed Jan. 4, 1971, Ser. No. 103,939

Term of patent 14 years

Int. Cl. D11—02

U.S. Cl. D35—3

FIG.-1

FIG. 1 is a side view of a flower pot with my new design; and

FIG. 2 is a top plan view of the flower pot.

The reverse side of the flower pot is identical to the side shown.

I claim:

The ornamental design for a flower pot, as shown and described.
